TOY ARCHER

Dominick N. Orlando and James W. Huber,
Erie, Pa.

Application June 21, 1939, Serial No. 280,410

7 Claims. (Cl. 46—145)

Our invention relates to new and useful improvements in toys.

An important object of our invention is the provision of a toy having the form of a human being and including a bow and arrow and mechanism for operating the same.

Another object of our invention is the provision of a toy archer that is adapted to simulate the movements of a human being in the shooting of the arrow.

Still another object of our invention is the provision of a game wherein the toy archer is provided with a manually operated mechanism for drawing the bow, and that is automatic in its action to release the same and to discharge the arrow.

Yet another object of our invention is to provide a toy of the above-mentioned character wherein the archer is positioned in a manner to discharge the arrow at a target remote therefrom.

A further object of our invention is to provide a game that will provide a great deal of pleasure and amusement to all who participate in the playing of the same.

A still further object of the invention is to provide a toy of the above-mentioned character that is simple in construction, efficient and efficacious in operation, and inexpensive to manufacture.

Other objects and advantages of our invention will be apparent during the course of the following description.

In the drawings, forming a part of this specification, and in which like numerals are employed to designate like parts throughout the same,

Figure 1 is a side elevation of a device embodying our invention.

Figure 2 is a transverse sectional view taken on the line 2—2 of Figure 1.

Figure 3 is a fragmentary vertical sectional view taken on the line 3—3 of Figure 2.

Figure 4 is a fragmentary longitudinal sectional view showing the free end of the discharge tube and an arrow in association therewith.

Figure 5 is a fragmentary vertical sectional view taken on the line 5—5 of Figure 4, and

Figure 6 is a fragmentary transverse sectional view taken on the line 6—6 of Figure 5.

In the accompanying drawings, wherein for the purpose of illustration, is shown a preferred embodiment of our invention, the numeral 10 designates a supporting base adapted to receive a manikin 11 at the end 12 thereof and to receive the target 13 at the opposite end 14. The target

13 may be of any desired shape and is spaced above the base 10 by the supporting bracket 15.

The manikin 11 is here designated as representing an Indian, however, it is to be understood that the representation is not restricted to the same, but may be formed to represent any desired figure. The manikin here illustrated is vertically positioned in a standing posture and is formed with a forwardly extending arm 16. The discharge tube 18 is secured in appressed relation to the inner face 19 of the arm and is provided with a longitudinally extending slot 20 in the inner portion thereof. The outer end 22 of the tube extends substantially beyond the free end of the arm 16 and the inner end 23 thereof terminates adjacent the body of the manikin 11. The bow 21 may be made of wood, or any suitable resilient material, and the central portion 24 is attached to the free end of the arm 16 and engaging the outer side of the tube 18. The bow 21 is mounted in an upright position and the upper and lower ends 25 and 26 are curved laterally in a manner whereby the bow string 27 will frictionally engage the discharge tube 18 transversely of the longitudinal slot 20.

The companion arm 28 comprises pivotally connected links 29 and 30. The pin 33 pivotally connects the inner end 31 of the link 29 to the supporting bracket 32, which is positioned at substantially the shoulder portion of the manikin 11 and on the opposite side from the arm 16. The guide rod 34 is disposed centrally below the discharge tube 18 with the inner end 35 thereof embedded in the body of the manikin and with the outer end 36 thereof bent upwardly and welded or otherwise secured to the discharge tube, as illustrated in Figure 3. The outer end 39 of the link 28 is formed to simulate the hand of a human being and the end 37 of the bracket 38 is pivotally secured to the underside thereof by the vertical pin 39. The end 40 of the bracket 38 is formed with depending ears 41 and 42 which are slidably received by the guide rod 34, and the coil spring 43 is interposed between the ear 41 and the body of the manikin.

The bell crank 44 is pivotally mounted on the manikin below the arm 28 and the lever arm 45 thereof is formed with a flared finger receiving portion 46. The lever arm 47 is connected to the bracket 38 by the link 48.

The arrow 49 is provided with a suction cup 50 at the outer end 51 thereof and the inner end 52 is provided with a laterally extending shank 53. The arrow is adapted to be slidably received within the discharge tube 18 and with the lateral

shank 53 thereof projecting outwardly therefrom through the longitudinal slot 20.

The catch 54 is substantially cup shaped in its formation and includes a resilient arm 55 which extends laterally from the rim 56 thereof and has its inner end 57 riveted, or otherwise secured, to the link 30. The crown of the catch 54 is provided with an elongated slot 58 which receives the shank 53 of the arrow and the bracket 38 is recessed as at 59 so that when the arrow is inserted within the discharge tube 18 the shank 53 thereof will engage the bow string 27 to move the same rearwardly of the catch and to permit the shank 53 to be received within the slot 58. The resilient action of the arm 55 will hold the catch in close frictional engagement with the discharge tube 18 and retain the shank 53 in engagement therewith, as illustrated in Figure 4.

The operation of our device is as follows: When the arrow is received within the discharge tube 18 and with the lateral shank 53 thereof engaged by the catch 54 in the manner hereinbefore described, the operator of the toy may manually actuate the bell crank lever 44 by pressing downwardly on the lever arm 45 to slidably actuate the bracket 38 toward the body of the manikin against the resilient action of the coil spring 43. By virtue of the pivotal attachment of the link 29 with the bracket 32 and of the links 29 and 30 with each other, they will be moved into an acute angular relation and the arm, in its entirety, will project laterally from the body of the manikin in simulation of the actual movements of a human archer. As the bracket 38 is retracted toward the body of the manikin, the bow string 27, positioned rearwardly of the shank 53 of the arrow, will draw the bow 21 and when the bracket reaches the fully retracted position the laterally projecting stop element 60 will engage the catch 54, as illustrated by the dotted lines in Figure 2, to depress the same against the resilient action of the arm 55 and to move the same out of engagement with the shank 53. As soon as the shank is released, the tension of the bow will discharge the arrow from the tube with sufficient force to cause the same to strike the target 13 and the suction cup 56 carried by the arrow will cause the same to adhere to the target. As soon as the bell crank 44 is released, the coil spring 43 will move the bracket 38 forwardly on the guide rod 34 to move the arm 28 to the extended position preparatory to another arrow being inserted in the discharge tube.

It is to be understood that the form of our invention, herewith shown and described, is to be taken as a preferred example of the same, and that various changes in the size, shape and arrangement of parts may be resorted to without departing from the spirit of our invention, or the scope of the appended claims.

Having thus described our invention, we claim:

1. A device comprising a vertically disposed supporting figure, a slotted tube secured to and extending forwardly of the said figure, a bow including a bow string mounted in an upright position adjacent the free end of said tube, a lever pivotally carried by the figure laterally of the said tube, said lever comprising hinged sections, an arrow received by the tube and having a lateral shank adapted to ride in the said slot and to engage the said bow string, a catch having an aperture to receive the shank, said catch being attached to the free end of the said lever

by a resilient arm portion, manual means to move the free end of the lever toward the figure against the resilient action of the bow, and means to depress the catch against the resilient action of the said arm portion when the lever is in retracted position.

2. A device comprising a vertically disposed supporting figure, a slotted tube secured to and extending forwardly of the said figure, a bow including a bow string mounted in an upright position adjacent the free end of the said tube, a lever pivotally mounted on the figure and extending laterally of the said tube, said lever comprising hinged sections, an arrow received by the tube and having a lateral shank adapted to ride in the said slot and to engage the said bow string, a catch having an aperture to receive the shank and attached to the free end of the said lever by a resilient arm portion, manual means to move the free end of the lever toward the figure against the resilient action of the bow, means to depress the catch against the resilient action of the said arm portion when the lever is in retracted position, and spring means to return the hinged sections of the lever to the extended position.

3. A device comprising a supporting manikin formed with a forwardly extending arm portion, a slotted tube mounted in appressed relation to the inner side of the said arm portion, a bow attached to the free end of the said arm portion and with the bow string frictionally engaging the tube transversely of the said slot, a pair of links comprising an arm pivotally connected and connected to the said manikin, an arrow received in the tube and having a lateral shank adapted to ride in the said slot and to engage the bow string, a catch comprising an apertured cupular member having a spring arm connected to the free end of the said links, said apertured member being adapted to engage the lateral shank of the arrow, and actuating means to move the free end of the pivoted links toward the manikin to draw the said bow.

4. A device comprising a supporting manikin formed with a forwardly extending arm portion, a slotted tube mounted in appressed relation to the said arm portion and extending therebeyond, a bow attached to the free end of the said arm portion and with the bow string frictionally engaging the tube transversely of the said slot, a pair of links comprising an arm pivotally connected and connected to the said manikin, an arrow received in the tube and having a lateral shank adapted to ride in the said slot and to engage the bow string, a catch comprising an apertured cupular member having a spring arm connected to the free end of the said links and adapted to engage the lateral shank of the arrow, actuating means to move the free end of the pivoted links toward the manikin to draw the said bow, and means to release the catch from the shank of the arrow when the said links are in a fully retracted position.

5. A device comprising a supporting manikin formed with a forwardly extending arm portion, a slotted tube mounted in appressed relation to the said arm portion, a bow attached to the free end of the said arm portion and with the bow string frictionally engaging the tube transversely of the said slot, a pair of links comprising an arm pivotally connected to the said manikin, an arrow received in the tube and having a lateral shank adapted to ride in the said slot and to engage the bow string, a catch comprising an aper-

5 tured cupular member having a spring arm connected to the free end of the said links and adapted to engage the lateral shank of the arrow, manual means to move the free end of the
10 pivoted links toward the manikin to draw the said bow, means to release the catch from the shank of the arrow when the said links are in a fully retracted position, and spring means interposed between the free end of the second-mentioned
15 arm and the manikin, said spring adapted to be compressed upon retraction of the arm and to move the said arm into the extended position upon release of the said manual means.

6. A device comprising the combination of a
15 vertically disposed manikin, a slotted tube secured to and extending forwardly of the said manikin, a bow including a bow string mounted in an upright position adjacent the free end of the said tube, a lever pivotally carried by the manikin and
20 extending laterally of the said tube, said lever comprising hinged sections, a guide rod carried by the manikin and projecting forwardly thereof below the said tube, a bracket carried by the free end of the lever and slidable on the
25 said guide rod, an arrow received by the tube and having a lateral shank adapted to ride in the said slot forwardly of the bow string, catch means carried by the lever to engage the lateral shank of the arrow, means to slidably actuate the
30 bracket toward the figure, spring means interposed between the brackets and the manikin and adapted to be compressed upon retraction of the bracket, and means to automatically release the said catch from engagement with the shank of

the arrow when the said bracket is in the retracted position to permit the body to discharge the arrow and the spring means to return the lever to the extended position.

7. A device comprising the combination of a
5 vertically disposed supporting figure, a slotted tube secured to and extending forwardly of the said figure, a bow including a bow string mounted in an upright position adjacent the free end of the said tube, a lever pivotally attached to the 10 figure and extending laterally of the said tube, said lever comprising hinged sections, a guide rod carried by the figure and projecting forwardly thereof below the said tube, a bracket carried by the free end of the lever and slidable on the said 15 guide rod, a spring interposed between the brackets and the said manikin, an arrow received by the tube and having a lateral shank adapted to ride in the said slot forwardly of the bow string, catch means carried by the lever to engage the lateral shank of the arrow, a bell crank lever pivotally mounted on the supporting figure, link means connecting the bell crank lever and the said bracket so that actuation of the bell crank 20 lever will slidably actuate the bracket in the direction of the figure against resilient action of the said spring means, and means to automatically release the said catch from engagement with the shank of the arrow when the said bracket is
25 in the fully retracted position to permit the body to discharge the arrow and the spring means to return the lever to the extended position.

DOMINICK N. ORLANDO.

JAMES W. HUBER.
